(57) **CLAIM**

We claim the ornamental design for a portion of a sawhorse, as shown and described.

DESCRIPTION

FIG. 1 is a perspective view of portion of a sawhorse according to the invention.

FIG. 2 is a right side view of the portion of the sawhorse.

FIG. 3 is a left side view of the portion of the sawhorse.

FIG. 4 is a front elevational view of the portion of the sawhorse.

FIG. 5 is a top plan view of the portion of the sawhorse; and, FIG. 6 is a bottom plan view of the portion of the sawhorse. The broken lines are for illustrative purposes only and form no part of claimed design.
